UNITED STATES PATENT OFFICE.

STANLEY WOJTAN, OF MUSKEGON, MICHIGAN.

RAILWAY-TIE AND RAIL-FASTENER.

1,261,883.

Specification of Letters Patent.

Patented Apr. 9, 1918.

Application filed January 24, 1918. Serial No. 213,517.

To all whom it may concern:

Be it known that I, STANLEY WOJTAN, a citizen of the United States of America, residing at Muskegon, in the county of Mus-

5 kegon and State of Michigan, have invented certain new and useful Improvements in Railway-Ties and Rail-Fasteners, of which the following is a specification.

The primary object of the present invention is the provision of a metallic form of rail that is easy and inexpensive to manufacture arranged with means for securely locking rails in their operative positions thereof.

15 A further object of the device is to provide a form of metallic railway tie adapted for mounting rails thereon without perforating or locking the rails in any manner and requiring only the use of a wrench.

20 A still further object of the device is to provide a metallic tie that possesses great strength and durability arranged with a quick action securing means for locking rails thereon readily releasable whenever desired.

25 In the drawings forming a part of this application and in which like reference characters refer to corresponding parts throughout the several views,

30 Figure 1 is a side elevation of one form of my device with rails operatively assembled therewith and shown in vertical transverse section,

Fig. 2 is a top plan view thereof with one 35 of the rails removed.

Fig. 3 is a longitudinal vertical central sectional view of an end portion of the same,

Fig. 4 is a vertical transverse sectional view taken upon line IV—IV of Fig. 3,

40 Figs. 5 and 6 are perspective views of portions of the rail locking means employed therewith,

Fig. 7 is a view similar to Fig. 3 of a slightly different form of the device, being a 45 sectional view taken upon line VII—VII of Fig. 8,

Fig. 8 is a view similar to Fig. 4 of this second form of the device and

50 Figs. 9 and 10 are horizontal sectional views taken upon lines IX—IX and X—X respectively of Fig. 7.

55 Referring more in detail to the drawings, a tie 10 is provided in the form of an arch plate 11 mounted upon the flat bed-plate 12 and secured thereto in any desired manner such as by rivets 13. Transverse slots 14 are

provided in the top 15 of the arch plate 11 adapted for receiving the bases 16 of the railway rails 17 and suitably spacing the rails apart the distance of the gage of the road. 60

Locking means are employed for each of the rails for securing them to the tie 10 comprising a hook member 18, an anchor 19 and a tensioning nut 20.

The hook 18 comprises a block 21 having 65 a hook 22 at one end thereof with a curved face 23, whereby the block 21 is adapted to slide longitudinally within the arch plate 15 for positioning the hook 22 overlying the inner edge 24 of the rail base 16. A bolt 70 25 projects from the block 21 and extends outwardly of the adjacent open end of the tie 10 adapted for slidably receiving the anchor 19 thereon by extending the bolt 25 through a perforation 26 in the upright post portion 75 27 of the anchor. A finger 28 perpendicularly projects from the top of the post 27 having a curved upper face and whereby the anchor 19 closely fits within the arch plate 11 in slidable relations with respect to 80 the adjacent outer edge of the rail base 16 and over which edge the inner beveled end 29 of the finger 28 is adapted to project.

The positions of the hook 18 and anchor 19 in their operative arrangement with the 85 base 16 of one of the rails 17 is best illustrated in Fig. 3 of the drawings, it being understood that the nut 20 is threaded upon the bolt 25 outwardly of the anchor 19 for moving the anchor and the hook 18 toward 90 each other for locking said members upon the rail base 16 with the rail thereby secured to the arch plate 11. It will be seen that the rails 17 are each secured in a similar manner to the tie 10 at points adjacent 95 the opposite ends thereof, while the rails may be readily released from the hooks 18 and anchors 19 by removing the nuts 20 and at which times the rail 17 may be readily separated from the ties 10. 100

The form of the device herein illustrated in Figs. 7 to 10 of the drawings provides a tie 10' formed of an arch plate 11' of substantially the same form as the plate 11 heretofore noted while no base plate is employed, the opposite flanges 21' resting directly upon the road bed. A cut away portion or slot 14' is provided in the top 15' of the tie 10' adapted for the seating of a railway rail 22' therein. A saddle 23' is formed beneath 110 the slot 14' by downwardly sinking the portion of the plate 11' for forming the slot 14'.

A fastening means for the rail 22' consists of a hook 24' having a substantially rectangular shank 25' slidably positioned within the saddle 23' for engaging the free 5 end of the hook 26' over the inner edge of the base 27' of the rail. A finger 28' having a block 29' at its outer end is slidably positioned in the open end of the tie 10', an opening 30 being arranged in the block 29' 10 through which the shank 31 of the hook 24' extends. A nut 32 is threaded upon the outer end of the hook shank 31 for engaging the block 29' and forcing the finger 28' over the outer edge of the rail base 27'. 15 With the elements assembled as best illustrated in Fig. 7 of the drawings it will be seen that the hook portion 26' and the finger 28' will be tightened upon the rail base 27' by tightening the nut 32, thus preventing re- 20 moval of the rail 22'.

A strong and serviceable metallic tie is provided which may be easily and quickly locked to a rail and the rails therefore easily released at will.

25 What I claim as new is:—

1. A device of the class described comprising an arch plate having a transverse slot in the top thereof adapted to receive a railway rail, oppositely positioned hook and finger members slidably mounted within the top of said plate adjacent the opposite sides of said slot and adjusting connections for the said hook and finger operable adjacent the end of the plate whereby the said hook 30 and finger are adapted for locking engagement with the rail when positioned within said slot.

2. A device of the class described comprising an arch plate having a transversely arranged curved top provided with a transverse slot adapted for receiving the base flange of a rail, a block form of hook positioned inwardly of the slot slidably engaging the curved top of the plate with a portion 40 adapted for arrangement within the slot when the device is assembled, a finger member slidably arranged upon the said hook adjacent the outer end of the plate slidably engaging the curved top of the plate 45 and having a portion adapted to project within the slot when the device is assembled and adjusting connections between said hook and finger members.

3. A device of the class described comprising a tie having an arch shaped plate 55 provided with a transverse slot in the curved top thereof, a rail seated within the said slot, a hook member slidably arranged within the plate beneath the rail having a curved portion engaging the top of the plate and 60 overlying the adjacent inner edge of the base flange of the rail when the device is assembled, a finger member slidably mounted upon the hook member adjacent the outer end of the plate with a portion of the hook 65 member engaging the curved top of the plate and overlying the adjacent outer edge of the base flange of the rail when the device is assembled and adjusting means between the said hook and finger members whereby the 70 latter are adapted for locking upon the rail with the rail secured to the tie.

4. A device of the class described comprising a tie formed of an arch plate having transverse slots in the top thereof, a bed-plate secured to the bottom of said arch plate, rails seated within said slots, hooks 75 slidably positioned within the arch plate inwardly of the rails adapted for overlying the inner edges of the base flanges thereof, anchor members fitted within the outer ends of the arch plate slidably mounted upon the said hooks engaging the curved top of the arch plate adapted to overlie the adjacent outer edges of the base flanges of said rails 80 and adjusting means upon the outer ends of said hooks engaging said anchor members.

5. A device of the class described comprising a tie formed of an arch shaped plate having a downwardly struck saddle providing a transverse slot in the top thereof, the said slot being adapted to receive a rail therein, a rail locking hook positioned within said saddle slidably longitudinally of the plate with a hooked portion projecting within the slot from the inner edge thereof, a finger member adjustably mounted upon the said hook adjacent the outer end of the plate adapted for projecting inwardly of the outer edge of the slot during the operation of the 90 device and adjustable locking means arranged upon said hook in contact with the finger member at the outer end of the plate.

95 In testimony whereof I affix my signature.

STANLEY WOJTAN.
